UNITED STATES PATENT OFFICE.

EMIL MAYER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

ARRANGEMENT FOR HIGH-FREQUENCY SIGNALING ON HIGH-TENSION LINES.

Application filed August 8, 1922, Serial No. 580,517, and in Germany June 1, 1921.

In the use of transmitters and receivers for wireless telegraphy and telephony, which transmit or receive energy along an existing high tension line, there is always 5 a possibility that high tension current will pass into the radio frequency apparatus and result either in destruction of material or the endangering of human life. It has been proposed to overcome such danger by means 10 of fuses against high tension (sparking distance or choke coil). This invention provides a further means for decreasing the danger.

According to the invention, between the 15 transmitting apparatus or receiver and the element which serves to connect the transmitter or receiver energetically directly or indirectly to the high tension line, a protecting means is placed. This means consists, for 20 instance, of a plate sufficiently insulating the high tension current and placed between the primary and the secondary windings of transformers by which the transmitter or receiver is coupled to the high tension line. 25 The invention can also be utilized in such a way that this protecting plate is made the base plate of a switch board, in which case the conduits to the high tension line or to the transmitting antennæ are placed on one 30 side of the switch board, while on the other side, preferably on the front side, only the secondary winding and the radio frequency transmitting or receiving apparatus are mounted.

35 The invention may also be embodied in an arrangement which includes a capacitive coupling between the transmitting or receiving apparatus in which case the insulating plate, which may again be in the form of a 40 switch board, forms the dielectric of the coupling condensers.

Upon the accompanying drawing several modes of carrying out the invention are shown.

45 Figure 1 of the drawing is a diagrammatic representation of an arrangement embodying the invention, and in which the high tension line is inductively coupled to the transmitter or receiver;

50 Figure 2 is a view similar to Figure 1, but showing a capacitive coupling between the

high tension line and the transmitter or receiver;

Figure 3 is a view in front elevation of an insulating plate employed in accordance 55 with the invention and constructed in the form of a switchboard; and

Figure 4 is an end view of the arrangement shown in Figure 3.

In Figure 1, 1 denotes the primary and 2 60 the secondary winding, for instance, of a high tension transformer. 3 is an insulating plate which is placed between the two windings. The winding 1 is connected to the high tension transmission line while the 65 winding 2 is connected to the radio apparatus.

In Figure 2 a plate 6 connected, for instance, to the high tension line is separated by an insulating plate 3 from a plate 7 connected to the transmitter or receiver, thus constituting a capacitive coupling between the transmitter or receiver and the high tension line.

The reference character 4 in Figs. 3 and 75 4 designates a measuring instrument, such, for example, as an ammeter for measuring the current supplied from the radio transmitter 9 to the coil 10 supported on the front side of the base plate 3 of the switchboard. 80 The base plate 3 of the switchboard is composed of insulating material and on the opposite side of the plate 3 from the coil 10 is a coil 12 supported by clamps 5 and connected to the high tension line. The coils 85 10 and 12 on the switch board may be replaced by plates 7 and 6, shown in Fig. 2, which may be mounted on the base plate 3 of the switchboard in any suitable manner.

As shown in Figs. 3 and 4 the high tension 90 line is supported on one side of the switchboard 3, while the radio apparatus comprising the ammeter 4 and transmitter 9 is mounted on the other side of the switchboard.

Thus it will be seen by this arrangement the switchboard acts as a support for the high tension line, for the radio apparatus, and also the coupling coils, thereby insuring a complete and safe dielectric barrier between the high tension line and the radio apparatus precluding any danger of getting 100

the high potential of the transmission line into the radio apparatus. At the same time there is a good coupling between radio apparatus and the high tension transmission line.

Having described my invention, what I claim is:

1. In an apparatus of the class described, a high tension line, a switchboard to which the high tension line is connected, and an electromagnetic wave transmitter also connected with the switchboard, said switchboard being formed of insulating material and being arranged to insulate the transmitter from the high tension line so as to protect the operator of the transmitter from injury by the high tension current.
2. In an apparatus of the class described, a high tension line electromagnetic wave apparatus, and a switchboard to which the high tension line and the electromagnetic wave apparatus are respectively connected, said switchboard being formed of insulating material so as to protect the operator of the electromagnetic wave apparatus from injury by current from the high tension line.
3. In an apparatus of the class described, a high tension line, a coil to which the high tension line is connected, a switchboard upon which said coil is mounted, a second coil mounted on the opposite side of the switchboard from the first-mentioned coil, electromagnetic wave transmitter connected with said second coil, and a measuring instrument also mounted on said last-mentioned side of the switchboard for measuring the energy transmitted to the high tension line by the transmitter, said switchboard having a base plate composed of insulating material and interposed between said first and second coil for protecting the operator of the transmitter from injury by current from the high tension.
4. In apparatus of the class described, a

supporting board, a transmission line conductor supported by one side of said board, electromagnetic wave apparatus on the other side of said board and means for coupling said transmission line conductor and said electromagnetic wave apparatus together in such manner that the board precludes the access of the transmission line voltage to the electromagnetic wave apparatus.

5. In apparatus of the class described, a supporting board, a transmission line conductor on one side of said board, electromagnetic wave apparatus supported by the other side of said board, and means for coupling said transmission line conductor and said electromagnetic wave apparatus together in such manner that the said board precludes the access of the transmission line voltage to the electromagnetic wave apparatus.

6. In apparatus of the class described, a supporting board, a transmission line on one side of the board, electromagnetic wave apparatus on the other side of said board and means supported by said board for coupling said transmission line and said electromagnetic wave apparatus in such manner that said board precludes access of the transmission line voltage to the electromagnetic wave apparatus.

7. In apparatus of the class described, a switchboard of dielectric material, a transmission line conductor supported by one side of said switchboard, electromagnetic wave apparatus supported by the other side of said switchboard, and coils inductively coupled to each other, one coil being supported by one side of the said switchboard and connected to said conductor, and the other coil being supported by the other side of said switchboard and connected to said electromagnetic wave apparatus.

In testimony whereof I have signed my name to this specification.

DR. EMIL MAYER.
